Inventor

WILLIAM E. RIDEOUT

By Watson & Colman, Attorney

UNITED STATES PATENT OFFICE

WILLIAM EDMOND RIDEOUT, OF CROOKSTON, MINNESOTA

TUB STAND

Application filed May 16, 1929. Serial No. 363,568.

This invention relates to a tub stand and has relation more particularly to a device of this kind especially designed and adapted for use in connection with a washing machine, 5 and it is an object of the invention to provide a stand which is operatively connected to the machine so as to be available at all times.

Another object of the invention is to provide a device of this kind constructed in a 10 manner whereby various parts thereof are readily folded one with respect to the other and with respect to the machine with which it is associated so that when not in use the compacted or folded stand will lay close to 15 the machine, thus permitting the machine and stand to be conveniently stored away within a minimum of space.

A further object of the invention is to provide a stand of this kind which, when in extended or working position, provides an effective means for steadyng the machine and thus permitting the machine proper to be of a height whereby the operator may stand in a natural and comfortable position. This 25 particular advantage is emphasized by the fact that generally manufacturers of various types of washing machines recommend that the machine be somewhat low to eliminate vibration but with my improved stand the 30 machine is effectively steadied.

The invention consists in the details of construction and in the combination and arrangement of the several parts of my improved tub stand whereby certain important 35 advantages are attained and the device rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:—

Figure 1 is a view in perspective illustrating a stand constructed in accordance with an embodiment of my invention in extended or working position;

Figure 2 is a view in end elevation of the

stand with certain of the parts in a second position;

Figure 3 is a front elevational view of the stand as herein disclosed with certain of the parts in a second position and the washer 55 proper omitted;

Figure 4 is a view in end elevation of the stand opposite to that illustrated in Figure 2 with the stand partly folded, the complete raised position of the folded stand being dia- 60 grammatically indicated by broken lines.

As disclosed in the accompanying drawings, W denotes a washing machine of any desired make or type, said machine in Figures 2 and 4 of the drawings being fragmentarily indicated by broken lines.

One of the supporting legs 1 comprised in the structure of the washing machine has extending outwardly of its upper portion a bracket 2 and at the opposite side of the washer is a second outstanding bracket 3, herein disclosed as held to the housing 4 comprised in the transmission mechanism for the washer. It is to be understood, however, that I do not wish to limit myself to this particular location of the brackets 2 and 3 as they may be applied and secured in any manner which best complies with the requirements of practice which is determined by the type or character of washing machine with which my 75 improved stand is adapted to be employed.

In the present embodiment of my invention, my improved stand comprises two sections A and B. The section A comprises two elongated and parallel side members 5 and 6, the outer member 5 preferably constituting an angle iron while the inner member 6 constitutes an elongated flat strip. The members 5 and 6 adjacent to their opposite ends are tied or connected by the cross members 7 and 85 secured to the inner side members 6, preferably directly above the adjacent end portions of the cross member 7 are the leaves of the hinges 8, the other leaves of which being suitably fastened to the brackets 2 and 3. 90 These hinge connections 8 permit the stand section A to be readily swung upwardly when desired to be positioned in close proximity to the adjacent side face of the washer W.

Hingedly connected, as at 9, to each end 100

portion of the outer side member 5 of the section A is a supporting leg 10 of desired length and herein disclosed as an angle iron. When the section A is lowered and the legs 10 are in contact with the floor or kindred supporting surface, the section A is maintained in substantially a horizontal position as is clearly illustrated in the accompanying drawings.

10 The supporting legs 10 are connected or tied by the cross brace members 11 whereby said legs 10 are embodied in what may be termed a "unitary structure" so that said legs will swing in unison into folded position or into extended or working position. When in folded position these legs 10 are disposed closely adjacent to and in the same general direction as the cross members 7.

Depending substantially central from one 20 of the cross members 7 is a bracket 12 and pivotally connected with this bracket 12 and the adjacent leg 10 at a desired point spaced from its hinge 9 is an articulated brace member 14 constructed in a well known manner 25 and which serves to effectively hold the legs 10 in their extended or working position. The joint 15 comprised in this articulated brace 14 can be readily broken when it is desired to fold or compact the stand.

30 The section B comprises the parallel side members 16 of desired length, each of which being herein disclosed as constituting an angle iron and the inner portions of these side members 16 are hingedly connected, as at 17, 35 to the end portions of the adjacent extremities of the members 5 and 6 remote from the cross member 7 provided with the depending bracket 12.

The hinged connections 17 permit the section B to be swung over upon the section A so that when the section A is raised with respect to the washer W, said section B will be interposed between the section A and the washer.

40 45 The outer end portion of each of the side members 16 has pivotally connected thereto, as at 18, an end portion of a supporting leg 19, said leg having swinging movement toward and lengthwise of the adjacent side members 16 whereby said leg 19, when the stand is folded or compacted, will lie closely adjacent to said member 16. The supporting legs 19 are of a length, when extended, to support the side members 16 of the section B substantially coplanar with the side members 5 and 6 of the section A and said legs 19 are tied or connected by the crossed braces 20 permitting said legs 19 to have unitary swinging movement.

50 55 Each of the legs 19 and the adjacent side member 16 has associated therewith an articulated brace member 21 whereby the legs 19 are effectively maintained in their extended or working position, the joint 22 comprised in

said brace readily breaking when it is desired to fold or compact the stand.

The inner side member 16 of the section B adjacent its opposite end portions has hingedly connected thereto, as at 16', the elongated bars or arms 23 and 24 disposed in the same general direction as the cross members 25 connecting the opposite end portions of the member 16. The bar or arm 23 at the outer end of the section B is provided with a depending bracket 26 with which is pivotally connected an end portion of a brace bar 27.

70 75 The opposite end portion of this bar 27 is provided with an open slot 28 whereby said end portion may be readily engaged with an outstanding lug 29 carried by the adjacent supporting leg 19 resulting in effective means for bracing the bar or arm 23 in its extended or working position, yet permitting the bar 27 to be readily released when it is desired to swing said arm or bar 23 across the adjacent end portion of the section B when folding or compacting the stand. The bar or arm 24, as herein disclosed, when in extended or working position rests upon an outstanding 80 bracket 30 carried by the washer W. In folding or compacting the stand this bar or arm 24 is also swung across the section B.

85 90 When the stand is extended the sections A and B are adapted to have placed thereon tubs, said sections being of sufficient strength to effectively support said tubs when properly filled with water. The extended bars or arms 23 and 24 provide support for a clothes basket and with said clothes basket in convenient location with respect to the operator. When folded or compacted my improved stand lies closely adjacent to the washer proper as is believed to be clearly understood by the disclosure in broken lines in Figure 95 100 105 4. By this means the washer and stand when not in use can be stored away within a minimum of space.

110 It is to be noted that the various supporting legs 10 and 19 are not provided with casters but have direct contact with the floor or other supporting surface. This is of advantage in facilitating the steadyng of the washing machine by the stand when extended to effectively offset vibrations resulting from the working parts of the washing machine particularly when driven by a gasoline motor.

115 120 By thus steadyng and bracing the machine W it is possible to have such machine raised to a sufficient height to permit the operator to stand in a natural and comfortable position in contradistinction to the general practice of having the washers too low necessitating continued bending over of the person.

125 While I have hereinbefore described the bars or arms 23 and 24 as being adapted to be swung across the section B it is not imperative that this be done when the stand is being folded or compacted. If desired, these arms 130

or bars 23 and 24 may be swung upwardly into substantially vertical positions so that they pass by the washer back of the bar 6 of the section A when the section B is folded over upon said section A. In this arrangement the arm or bar 23 passes just over bracket 3 while the arm or bar 24 passes over the bracket 2, both of said arms hanging straight down when the section B is folded over on the section A. It is to be understood that the arms or bars 23 and 24 are of such length as to be free of the floor at this time.

From the foregoing description it is thought to be obvious that a tub stand constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with a support, a stand comprising two sections, means for hingedly connecting said sections one to the other whereby one section may swing over upon the other, means for hingedly connecting the second section with the support to permit the folded sections to swing closely adjacent to the support, supporting legs hingedly connected to each of the sections, supporting bars hingedly connected to one of the sections, said bars being angularly disposed from said section when extended, and means for supporting said bars when extended.

2. In combination with a support, a stand comprising two sections, means for hingedly connecting said sections one to the other whereby one section may swing over upon the other, means for hingedly connecting the second section with the support to permit the folded sections to swing closely adjacent to the support, supporting legs hingedly connected to each of the sections, supporting bars hingedly connected to one of the sections, said bars being angularly disposed from said section when extended, and means coacting with one of the bars and a supporting leg for the section for holding said bar when extended, and means carried by the support for holding the second bar when extended.

3. In combination with a support, a stand comprising a plurality of sections, hinged supporting means for hingedly securing one of said sections to the support, hinge means for securing a second section to said first section, hinge means for securing a third section to said section, bracing means for said third section, leg members hingedly secured to said

first and second sections, and link means secured to said first and second sections for foldably holding the leg members on said sections.

In testimony whereof I hereunto affix my signature.

WILLIAM E. RIDEOUT.
